(57) **CLAIM**

I claim the ornamental design for a multi-purpose utility knife, as shown and described.

DESCRIPTION

FIG. 1 is a front diagonal perspective view of the incentive utility knife, inclusive of the knife blades thereof.

FIG. 2 is a top view thereof, without the knife blades in the knife body.

FIG. 3 is a bottom elevational of FIG. 2.

FIG. 4 is left side elevational view including the knife blades.

FIG. 5 is a right side elevational view, without the knife blades.

FIG. 6 is a bottom view of the utility knife with the knives thereof in place.

FIG. 7 is rear elevational view of FIG. 5; and,

FIG. 8 is a front elevational view of FIG. 5.
